HAMMER CRUSHER

Original Filed Aug. 25, 1928

UNITED STATES PATENT OFFICE

GEORGE W. BORTON, OF NEW LISBON, NEW JERSEY, ASSIGNOR TO PENNSYLVANIA CRUSHER COMPANY, OF NEW YORK, N. Y., A CORPORATION OF NEW YORK

HAMMER CRUSHER

Original application filed August 25, 1928, Serial No. 302,080. Divided and this application filed June 6, 1929. Serial No. 368,819.

This application is a division of my application for patent filed August 25, 1928, Serial No. 302,080.

My invention relates to crushing structures of the character or type known as hammer mills, that is to say, structures which involve a supporting base, a suitable housing or frame mounted thereon and enclosing a chamber receiving the material to be crushed 10 and including a cage or screen made up of suitable grate bars, a breaker plate (or plates), and a rotor structure carrying a series of hammers designed to act upon the material to be crushed. The machine is of massive and rigid construction and is designed to receive what is known as "steam shovel feed" 15 or the contents of a quarry car, which may be delivered directly into the hopper leading to the crushing zone.

20 My present improvements have been applied to a structure of the type set forth in my pending application filed August 25, 1928, Serial No. 302,080, wherein I have described a machine highly efficient for the crushing 25 of material by what may be termed up-running hammers, that is to say, hammers which pass upwardly between grid bars located in the feed chute or hopper and which serve as temporary supporting means for the material operated upon. These hammers in their 30 up-running action tend to lift the larger pieces of material in addition to the incremental breaking or crushing action imparted thereto; thereby agitating material of mixed sizes, avoiding packing of the feed and insuring proper reduction of the material temporarily supported by the grid bars for passage through the latter, substantially by gravity, into the path of the down-running 35 hammers for further reduction in cooperation with the bars of the cage or screen.

An important feature of my improved crushing structure resides in the upper part 40 of the chamber comprising the feed chute or hopper into which the material to be crushed is dumped; one wall of the same being in the form of a heavy, reinforced plate, preferably curved and partially overhanging the hopper, which wall or plate may be pivotally 45 connected to the frame or housing.

One object of my invention is to provide means whereby the material to be crushed may be retarded in its movement through the hopper and temporarily supported in a position to be engaged by the hammers of the rotor structure in their up-running or overhead movement, and for this purpose I provide a series of grid bars projecting into the hopper space and which may extend part way 55 or entirely across the path of the feed and lying over the rotor structure; the hammers of such rotor structure passing between said bars and initially engaging such material before it passes to the lower portion of the crushing chamber. 60

These grid bars temporarily support the larger pieces of material while the hammers are incrementally nipping them down and prevent such larger masses crowding in on 65 the hammers and choking the crusher. 70

A further object of my invention is to provide the pivotally mounted breaker wall of the chute or hopper with projecting members, for cooperative association with grid bars extending part way or entirely across the hopper above the rotor structure; said projecting members being adjustable with respect to the wall of the hopper and toward and from the ends of the shorter grid bars 75 and being available for the dislodgment of any large masses which tend to jam in the hopper and lie out of range of the hammers. 80

These projecting members also help support the larger pieces of stone or other material, in conjunction with the grid bars, while the hammers are nipping it; thereby preventing choking of the crusher by the premature entrance of the larger pieces of stone or other material into the more active portion 85 of the hammer zone.

These and other features of my invention are more fully described hereinafter; reference being had to the accompanying drawings, in which:

Figure 1 is a cross sectional elevation, more or less diagrammatic in character, illustrating a form of hammer crusher mechanism within the scope of my invention, and

Fig. 2 is a sectional plan view of a portion 90

of structure shown in Figure 1, taken on the line II—II.

Like the structure of my pending application above referred to, my present structure comprises a base 1, supporting a frame or housing, indicated generally at 1^a, which may be made of structural metal and/or heavy cast parts suitably secured together and supporting the various elements making up the crushing structure, and more fully referred to hereinafter.

A screen or cage 2, which may be made up of arcuate side members 3, supporting a series of bars 4, is disposed in the base portion of the structure; such screen as a whole being pivotally supported on a shaft 5 disposed at one end of the machine, and adjustably supported at the opposite end; preferably by chains 6, passing over pinions 7, carried by a shaft 8; which chains may be adjusted as desired to elevate or lower the right hand end of the cage or screen by imparting rotative movement to the shaft 8. The bars 4 may be of the type illustrated in my Patent No. 1,624,886, dated April 12, 1927, or like those shown in the co-pending application of Oscar Anderson, filed July 24, 1928, Serial No. 295,039. The shaft 5 supporting the left hand end of the cage or screen, as illustrated in the drawings, may be of the adjustable type, such as illustrated in the patent of Charles R. Rouse, No. 1,695,562, dated December 18, 1928.

Within the crushing chamber provided by such cage or screen and above the latter a hammer-carrying rotor structure is mounted, which may comprise a shaft 10, journaled in suitable bearings 11; end plates 12; a series of disks 13 arranged between said end plates; rods 14 extending longitudinally of the rotor structure and passing through said disks and secured to said end plates, and hammers 15 which are pivotally hung on said rods. Hammer-carrying rotor structures of this general type are well known in the art and the hammers may be of any suitable type; preferably of massive and heavy construction, which may have renewable tips in order that wear may be compensated for and fresh tips supplied without removing the shanks of the hammers from the suspension rods 14.

The chute or hopper into which the material to be crushed may be delivered is indicated generally at 20, and is partly overhung by a curved breaker wall or plate 21, forming one end of the crusher structure and which may comprise a reinforced frame or plate of heavy construction. This frame or plate may be pivotally mounted on the shaft 5 which supports the cage or screen and may have its inner and partially overhanging face provided with a series of renewable wear members 22, which may be secured to said frame or plate by suitable bolts, as indicated at 23.

In order that the delivery of material into the crushing zone may be retarded to a certain extent and the desired reduction by the hammers insured, I provide a series of grid bars 25 in the chute or hopper, which bars may extend part way across the lower portion of the chute or hopper; such grid bars being disposed in relatively fixed position. They lie in such position as to temporarily support the larger masses of material fed into the hopper while the latter are being acted upon by the up-running hammers 15, moving in the direction of the arrow *a*, until such larger masses have been reduced or broken to a size that will permit passage through the spaces between or beyond the grid bars for further action by the hammers 15, cooperating with the bars 4 of the cage or screen, in the final crushing chamber of the machine.

The wall 21 of the hopper or chute, which is curved and partially overhangs the grid bars, may be provided with a series of relatively fixed wear plates, indicated at 22. For the purpose of temporarily supporting the material to be crushed additional retarding means may be provided, and one of these plates, that indicated at 22^a for instance, may be provided with a series of adjustable members in the form of rods 30 extending through said wear plate; which projecting rods may be disposed above the grid bars 25 or set in any manner with respect to the same that may be desired. The position of these projecting rods is such that they afford additional means for retarding the delivery of the material to be crushed and for this purpose they may be set at various angles and secured in position by any suitable means that will permit them to function in the proper manner.

By providing the rods 30 with racks, indicated at 30^a, longitudinal motion may be imparted to them by means of pinions 31, mounted on a shaft 32 which may be journaled in the reinforced frame or plate forming the curved wall 21; a hand wheel 33 serving to rock said shaft 32 and effect the desired movement of said rods 30 when it is desired to adjust the same. This movement may also be employed to dislodge any masses of material which may have been wedged in the lower part of the chute above the grid bars. In lieu of such operating means for these bars, they may be set in the desired position (or positions) by hand and held therein by adjustable wedges.

The rods 30 are associated with the grid bars 25, which may extend partially or entirely across the lower end of the chute or hopper. The shorter grid bars when employed may terminate at a point just beyond the vertical axis of the rotor structure, or at any desired point where they will perform the desired function. The short grid bars may be of the type disclosed in the co-

pending application of Charles A. Jamison, filed August 25, 1928, Serial No. 302,108, and may be adjustable in the manner disclosed therein.

The cage or screen structure comprises the arcuate side members 3, connected together by suitable spacing cross members 3^a, 3^b, et seq.; such side members being hung on the shaft 5 at one end (which shaft may be of the type disclosed in the application of Rouse, before referred to), and supported at the opposite end by chains 6, passing over the pinions 7, carried by the shaft 8.

A tramp iron pocket may be arranged at the right hand side of the machine, as illustrated in Fig. 1, just beyond the end of the cage or screen. At such part of the machine the cross section 21^a of the frame which extends between the side walls of the structure and serves as a support for the grid bars 25 is arched, and receives a wear plate 71 which may extend part way into the crushing chamber; being notched at 72 for the passage of the hammers. An opening 73 is provided between a lower cross member 21^b and said plate 71, and uncrushable material discharged through said opening 73 may drop onto the shelf provided by said cross-member 21^b. It will be seen therefore that any tramp iron in the form of spikes, bolts, nuts and/or the like or other uncrushable material in the path of the hammers will be forcibly thrown against this arched wear plate 71 and be discharged from the crushing zone.

It will be understood, of course, that the several walls of the machine, including the chute or hopper, will be provided with the usual wear plates, and that the side members 3 of the cage or screen will carry the usual shedding members designed to shed or direct material being crushed into the path of the hammers and through the spaces between the bars of the screen or cage.

As in the machine of my pending application above referred to, the bottom of the feed chute or hopper formed by the grid bars 25, cuts into the up-running hammer circle at a point below the high point of the same; in other words, the up-running hammers have an opportunity of impacting the stone on an up grade for a considerable portion of the arc of the hammer circle, before the center or highest part of the hammer circle is reached. This is believed to be a distinctly advantageous feature of construction, as large pieces of stone or other material are retarded in going uphill and this additional time element gives the hammers better opportunity in the early stages, when the pieces of stone or other material are large, for the important and heavier preliminary breaking, so that when the uncrushed material gets up to the zenith or highest portion of the circle and starts downward at increased speed, it is better adapted, by reason of its size, to take the bal-

ance of the ride down hill to the left of the zenith, when its speed would be faster and where the lesser but no less important secondary crushing takes place. In other words, it seems distinctly better that the larger pieces 70 of material particularly, which are the most difficult to reduce, are presented to the hammer circle on an up grade and at slower speed, rather than at the top of the circle where they would be more rapidly carried into a down hill position. This condition would give the hammers less time to do the preliminary heavy crushing, which would mean that the material would enter the rapidly restricting zone 75 between the hammers and the breaking surface of the wall or plate 21, in appreciably large sizes; thereby causing congestion of work in this restricted zone; reducing the chance for a complete and final reduction 80 from the hammer action, with increased wear and shock to the machine, and the necessity of increased power because the total reduction period would be considerably increased.

I claim:

1. In a crushing machine, the combination 90 with a frame having a hopper and a breaker wall structure pivotally connected to said frame and partly overhanging said hopper, a screen adjustably mounted in the lower portion of said frame and below said overhanging breaker wall structure, a rotor structure carrying hammers cooperating with said screen, and a series of grid bars in the lower portion of said hopper above the screen, of adjustable bars projecting into said hopper in substantial alignment with said grid bars and serving with the latter to temporarily retard the passage of material to be crushed whereby said material may be subjected to the action of said hammers in their up-running movement while temporarily retarded.

2. In a structure such as set forth in claim 1, adjustable members carried by the breaker wall structure and adapted to be projected into the hopper space to serve as additional retarding means to temporarily support the material to be crushed and to displace masses thereof jammed in the bottom of said hopper.

3. In a structure such as set forth in claim 1, adjustable members carried by the breaker wall structure and adapted to be projected into the hopper space to serve as additional retarding means to temporarily support the material to be crushed and to displace masses thereof jammed in the bottom of said hopper, and means for operating said projective members.

4. In a structure such as set forth in claim 1, a series of adjustable rods carried by the pivotally mounted breaker wall structure and projecting into said hopper in substantial alignment with said grid bars, and means for moving said rods toward and from the ends of said grid bars.

5. In a structure such as set forth in claim 1, a series of adjustable rods carried by the pivotally mounted breaker wall structure and projecting into said hopper opposite the ends of said grid bars, and means for moving said rods toward and from the ends of said grid bars.
  6. In a structure such as set forth in claim 1, a series of adjustable rods carried by the pivotally mounted breaker wall structure and projecting into the hopper space, racks formed on said rods, pinions engaging said racks and means for operating said pinions.
  7. In a hammer crusher, the combination with a frame providing a crushing chamber, a pivotally supported screen forming the lower portion of said crushing chamber, rotating hammers within said chamber, a chute delivering into said crushing chamber and having a curved wall, and grid bars extending part way into the chute and between which said hammers may pass, of adjustable projections carried by one of said breaker plates and extending into the chute opposite the ends of said grid bars for retarding delivery of the material under treatment.
  8. In a hammer crusher, the combination with a frame providing a crushing chamber, a pivotally supported screen forming the lower portion of said crushing chamber, rotating hammers within said chamber, a chute delivering into said crushing chamber and having one wall constituting a breaking surface, and grid bars extending into the chute between which said hammers may pass into engagement with material temporarily supported thereby, of adjustable projections carried by said breaking surface and extending into the chute; said projections cooperating with said grid bars to retard delivery of the material under treatment.
  9. A hammer crusher comprising a frame having a crushing chamber in the lower part of the same, a hopper in the upper portion of the frame delivering into said crushing chamber, a series of spaced bars in the lower part of said hopper serving to retard the feed, a series of adjustable rods projecting into said hopper in substantial alignment with said spaced bars, and a series of rotating hammers acting between said spaced bars to reduce the material lying upon the same before it reaches the crushing chamber.
  10. A hammer crusher comprising a frame having a crushing chamber in the lower part of the same, a hopper in the upper portion of the frame delivering into said crushing chamber, a series of rods projecting into the hopper and adjustable longitudinally; said rods serving to retard the feed, and a series of hammers acting with respect to said rods to reduce material intercepted thereby before it reaches the crushing chamber.
- In witness whereof I have signed this specification.

GEORGE W. BORTON.
